Primary Examiner — Mimosa De(74) *Attorney, Agent, or Firm* — Ferguson Case Orr Paterson(57) **CLAIM**

The ornamental design for a racing simulator cockpit, as shown and described herein.

DESCRIPTION

FIG. 1 is a front perspective view of a racing simulator cockpit of the present invention.

FIG. 2 is a rear perspective view of a racing simulator cockpit of the present invention shown in FIG. 1.

FIG. 3 is a front view of a racing simulator cockpit of the present invention shown in FIG. 1.

FIG. 4 is a rear view of a racing simulator cockpit of the present invention shown in FIG. 1.

FIG. 5 is a right side of a racing simulator cockpit of the present invention shown in FIG. 1.

FIG. 6 is a left side view of a racing simulator cockpit of the present invention shown in FIG. 1.

FIG. 7 is a top view of a racing simulator cockpit of the present invention shown in FIG. 1; and,

FIG. 8 is a bottom view of a racing simulator cockpit of the present invention shown in FIG. 1.

Elements of the mechanisms in the attached figures that are in broken and/or phantom lines are shown for illustrative and/or environmental purposes only and form no part of the claimed design.
